FOUNTAIN PEN

William O. Tassie, St. Boniface, Manitoba, Canada, assignor of one-half to James Armstrong Richardson, Winnipeg, Manitoba, Canada

Application May 25, 1934, Serial No. 727,535

5 Claims. (Cl. 120—47)

This invention relates to improvements in fountain pens and an object of the invention is to provide a fountain pen which is filled by external suction means consisting of a capping sleeve capable of being rendered air tight and slidable against the external surface of the barrel.

5 A further object of the invention is to provide a fountain pen of which the whole barrel may be filled with writing fluid.

10 A further object of the invention is to provide a fountain pen having a minimum number of wearing parts.

A further object is to provide a pen which consists of fewer parts than other fountain pens at 15 present in use.

A further object of the invention is to provide a fountain pen, the reservoir of which may be filled with only one stroke and with less labor and less loss of time than has hitherto been possible.

20 A further object is to provide a pen which will not occasion the necessity for new equipment incidental to its manufacture.

A further object is to provide a pen which can 25 be manufactured more cheaply than any existing pen.

A further object is to provide a pen which can be made of the same material practically throughout.

30 A further object is to provide a fountain pen having no metal, soft rubber or fragile material in its assemblage.

A further object of the invention is to provide a fountain pen which may be automatically prevented from overflowing when filled to capacity.

35 A still further object of my improved fountain pen is to provide a barrel which will not have to be internally machined.

A still further object of my invention is to provide 40 a fountain pen which can be varied in respect of the diameter to suit the needs of various writers.

With the foregoing objects in view and such other objects as may appear as the specification proceeds, my invention consists in the arrangement and construction of parts all as hereinafter more particularly described, reference being had to the accompanying drawings, in which:—

Fig. 1 is a central longitudinal sectional view of my fountain pen but showing the nib in full.

50 Fig. 2 is a perspective view of my fountain pen.

Fig. 3 is a sectional detail of the valve, valve cap and associated parts.

Fig. 4 is a sectional detail of the external collar and annular packing groove.

55 In the drawings like characters of reference

indicate corresponding parts in the different figures.

Considerable inventive ingenuity has been expended upon improvements in self filling fountain pens since their introduction. To the best 5 of my knowledge, however, all these improvements have consisted of means for creating a vacuum within the reservoir of the pen either by means of an internal piston or by various forms of rubber sacs.

10 My invention, however, consists of a radical departure from any of the foregoing embodiments and includes a cylindrical barrel portion A surrounding a writing fluid reservoir B, a capping sleeve C of greater diameter than the external 15 diameter of the barrel and slidable thereon in association with a barrel circumscribing collar D.

A nib 10 together with the usual feeding device (not shown) is provided at one end of the barrel and at the opposite end is a screw cap 11 having 20 an obliquely disposed passageway 12 extending therethrough. The upper end of the barrel is internally threaded as at 13 to receive the valve cap and it will be observed that by partially unscrewing the valve cap, the passageway 12 which 25 emerges onto the thread of the valve cap, becomes exposed, thereby permitting the entry of air into the valve.

It will be observed that the interior 14 of the 30 valve cap is in the form of a truncated cone and within this cone is a similarly shaped float valve 15 provided with a central orifice 16. Upon the periphery of the valve cap extending inwardly is a small projection 17, for the purpose of preventing the float valve 15 from falling into the 35 barrel when the quantity of writing fluid in the reservoir is not sufficiently high to keep the valve afloat.

The barrel circumscribing collar D is composed 40 of the same material as the main portions of the fountain pen, viz. barrel capping sleeve, etc. and is provided with two opposed threads 18 and 19 tapering outwardly from the barrel towards each other and spaced apart by means of a flattened band portion 20.

45 An annular recess 21 extends around the inner face of the member D and this recess is provided with a leather packing ring 22 which is inserted within the recess. Thus the collar D forms a substantially air tight member slidable 50 upon the barrel.

The capping sleeve C is slightly shorter in length than the reservoir but is of greater diameter. It is provided at its open end with an internally threaded portion 23 and at a point ad- 55

jacent its opposite end, I provide two diametrically opposed air holes 24. The usual band 25 embraces the lower end of the capping sleeve for the purpose of lending reinforcement thereto.

5 The threaded end of the sleeve is engageable with either of the threads 18 or 19 of the collar D. Thus, when the pen is not in use, the sleeve will be in engagement with the threads 18 and in use, will be in engagement with the threads 10 19. The threads 18 and 19 have been tapered for reasons which are now apparent, namely, in order to prevent the capping sleeve from sliding from its appointed position on the barrel when the pen is in use or out of use. When the capping sleeve is only slightly turned onto the threads, it is possible to pull the collar up and down with comparative ease. When, however, the threads are turned to a greater extent upon the collar, it becomes increasingly difficult to 15 move same due to its binding action upon the barrel.

10 The manipulation of my pen will now be explained.

When it is desired to fill the pen, assuming the pen to be uncovered and the capping sleeve covering the opposite end of the barrel to the nib, the sleeve is unscrewed from the member D and the valve cap 11 turned to expose the external orifice of the passageway 12. It should be noted, 20 however, that if desired, the collar D may be drawn completely off the barrel with the capping sleeve preparatory to unscrewing the valve cap.

Having unscrewed the valve cap, the capping sleeve and collar are rammed down and the pen 25 inserted in the ink. The forefinger and thumb are placed over the orifices 24, thereby rendering the sleeve air tight. The sleeve and the collar are now drawn upwardly and writing fluid is sucked into the reservoir B by the vacuum 30 caused through the upward travel of the air tight sleeve which interconnects with the reservoir through the temporarily opened passageway 12.

When the writing fluid in the reservoir reaches 35 the float valve, said valve rises and seals the internal orifice of the passageway 12, thus preventing the overflowing of ink through the passageway into the sleeve. The pen having now been filled, the forefinger and thumb are 40 removed from the orifices 24 and if desired, the collar withdrawn from the barrel. The valve cap is screwed tight and the pen is full.

To cover the pen when out of use, the capping sleeve is slacked off the thread 19 and the sleeve 45 and collar or the sleeve alone removed from the barrel. It can then be placed over the opposite end of the barrel and the threaded end of the sleeve jammed tight against the tapered thread 18.

60 From the foregoing, it will be seen that my invention utilizes an external method of filling a fountain pen which is completely at variance with the methods used hitherto.

A further feature of this pen is that those 65 persons who prefer a slender pen, may tighten the collar against the barrel fairly high up while those who prefer a pen of greater diameter, will have the sleeve drawn downwardly so that the collar is adjacent the base of the reservoir.

70 The reduced cost of manufacturing such a pen as I have described, will be clearly seen. As pre-

viously mentioned, it has fewer parts in its assemblage and among other advantages, the interior of the barrel does not require machining such as is the case with piston filled pens. The only part that can possibly become worn is the leather packing ring 22 and obviously this will last a great many years before replacement is required.

5 Since various modifications can be made in the above invention, and many apparently widely different embodiments of same, made within the scope of the claims without departing from the spirit and scope thereof, it is intended that all matter contained in the accompanying specification shall be interpreted as illustrative only 10 and not in a limiting sense and I desire only such limitations placed thereon as are specifically expressed in the accompanying claims.

What I claim as my invention is:—

1. Improvements in fountain pens comprising, 20 in combination with a barrel, reservoir and writing point, means for drawing fluid into said reservoir comprising a capping sleeve provided with orifices capable of being manually sealed, a threaded collar encircling the exterior of said barrel, a packing ring within said collar, a valve cap upon said pen, a float valve within said valve cap, a passageway extending through said valve cap, said passageway permitting communication between the interior and exterior of said valve 25 upon manual operation thereof, said float valve acting to seal the interior orifice of said passageway when the level of the float within the reservoir reaches said valve.

2. Improvements in fountain pens comprising, 35 in combination with a barrel, reservoir and writing point, means for inducing suction within the pen comprising a closed capping sleeve, a barrel encircling collar slidable upon said pen and means for attaching said capping sleeve to said collar 40 upon either side thereof.

3. Improvements in fountain pens comprising, 45 in combination with a barrel, reservoir and writing point, means for inducing suction within the pen comprising a closed capping sleeve having orifices therein slidable upon the barrel of the pen, a valve seating threadably engaged with the barrel of the pen, a float valve provided with an orifice within said seating and a passageway communicable between the reservoir and the exterior of the pen upon the unscrewing of said valve seating.

4. Improvements in fountain pens comprising, 55 in combination with a barrel, reservoir and writing point, means for inducing suction within the pen comprising a closed capping sleeve, a barrel circumscribing element slidable upon said barrel attachable to said capping sleeve, a valve seating in threadable engagement with said barrel, a float valve provided with an orifice held within said 60 valve seating and a passageway within said valve seating communicable between said reservoir and the exterior of said pen upon the unscrewing of said valve seating.

5. The device as claimed in claim 3 in which 65 said capping sleeve is provided with a slidable annular recessed collar portion at the lower end thereof and attached thereto and packing within said recessed collar portion.
